MAGNETIC INDUCTION DEVICE FOR
ACCELERATING ELECTRONS

Rolf Wideröe, Zurich, Switzerland, assignor to
Aktiengesellschaft Brown, Boveri & Cie, Baden,
Switzerland, a joint-stock company.

Application January 7, 1947, Serial No. 720,544
In Switzerland August 6, 1946

12 Claims. (Cl. 250—27)

1 This invention relates to devices for accelerating electrically charged particles such as electrons to high velocity and hence high potential by means of magnetic induction effects. These devices which are now known generally as ray transformers or betatrons are comprised generally of an evacuated annular tube into which electron streams are discharged from an electron emissive cathode, and a magnetic system energized by alternating current which produces a magnetic field varying cyclically with time and having a space distribution such that the injected electrons are accelerated by the field round and round the tube on an orbital path known as the "equilibrium circle". The magnetic field divides into two components; one component called the "inducing field" produces the electron acceleration; the other component called the "control field" produces a centripetal effect upon the electrons to offset the centrifugal forces of the electrons caused by their motion along the circular path thereby enabling the electron stream to be confined during acceleration to an equilibrium circle of substantially constant radius. The electron streams accelerate to high velocity during a quarter cycle of the magnetic field and are at such time diverted from the equilibrium circle for producing desired results such as for example to bombard a target and give off X-rays that are used in the treatment of diseases.

In the interest of efficiency it is desirable to operate a betatron on both halves of the wave of the alternating current power supply used for producing the magnetic field referred to above, and with this type of operation an electron stream is accelerated in one direction around the tube during a part of one-half of the cycle of the alternating current power supply, and another electron stream is accelerated in the opposite direction around the tube during a part of the other half of the alternating current cycle. Since the two electron streams each separated from the other by substantially a half cycle of the power current move in opposite directions when diverted from the equilibrium circle to impinge upon the anode, the electron streams are each ordinarily used for the X-ray treatment of different objects. The present known betatron constructions using a pair of electron streams have the disadvantage that both electron streams always have the same intensity and velocity. When the betatron is used for medical purposes, these limitations, namely like intensity and speed of the electrons are a considerable drawback,

since one will rarely ever find two patients at the same time who require exactly the same intensity of radiation or ray hardness.

The object of this invention is to provide an improved construction for a betatron using a pair of oppositely running electron streams by which one may selectively control both the intensity and speed of each electron stream independently of the other.

Other objects and advantages to be derived from the invention will become more apparent from the following detailed description and from the accompanying drawings which illustrate preferred constructions.

15 In the drawings, Fig. 1 is a vertical central section of a magnetic induction accelerator embodying one form of the invention; Fig. 2 is a horizontal section taken along line 2—2 of Fig. 1 showing a fragmentary section of the annular tube and a control circuit for one of the electron emitting cathodes; Figs. 3 and 4 are views similar to Fig. 2 but illustrating modified forms of the invention by which independent control of the two electron streams is attained; Fig. 5 is a circuit diagram showing a circuit by which independent control over the respective ejection velocities of the two electron streams is brought about; and Fig. 6 is a plot of the induction flux curve showing its variation with time.

Referring now to the drawings and in particular to Figs. 1 and 2, the magnetic induction accelerator which is symmetrical about the axis *a*—*a* is comprised of a magnetic field structure 10 made up from steel laminations of appropriate contour and includes a pair of cylindrical pole pieces 11—11' separated by air gap 12 located concentrically along axis *a*—*a*, and a pair of annular pole pieces 13—13' facing each other and separated by air gap 14. Yoke members 15 complete the magnetic circuit for the cyclically varying flux set up in the annular and cylindrical pole pieces. Poles 11—11' and 13—13' are surrounded by an annular winding preferably split into two coil sections 16—16' which are connected in series for energization from a source of alternating current of suitable frequency such as for example 100 cycles/sec. applied to terminals 17.

An annular evacuated glass tube 18 rests in the air gap 14 between the pole pieces 13—13' and thereby surrounds a part of the axial pole pieces 11—11'. For producing the two electron streams, a pair of coiled filamentary cathodes 20, 21 are used and these extend for a substantial distance in a direction parallel to the axis

of symmetry of the tube 18. The cathodes are suitably supported within and near the outer wall of tube 18 and are partially enclosed within opposite sections of an H-shaped electrode 22 that is positively charged relative to the cathodes 20 and 21 through ground and which serves to initially guide the electron streams alternately emitted from cathodes 20, 21 in a direction generally tangential of the tube 18. As will be more fully explained in succeeding paragraphs, the two electron streams alternately emitted from cathodes 20, 21 for a brief instant at the start of each half cycle of the magnetic field produced by windings 16-16' are then accelerated respectively under the influence of the changing field. When the electron streams reach their ultimate desired velocity which occurs not later than one-quarter of a cycle later, providing the magnetic control field is not premagnetized as described in my copending application Serial No. 708,552 filed November 8, 1946 they are each in turn pulled radially inward from the equilibrium circle k to impinge upon the anode 23. In the drawing, the electron stream emitted from cathode 21 is shown by arrow 24 striking the target anode 23 and producing X-rays indicated by arrow 25.

In accordance with the invention, independent control is exercised over the characteristics of the electron streams emitted from cathodes 20 and 21. The circuit by which the electron stream emitted from cathode 21 is controlled includes a transformer 26 for heating the cathode, the secondary side 26b of the transformer being connected in circuit with cathode 21 while the primary side 26a is connected through a regulating resistance 27 to a source of alternating current applied to terminals 28.

The instant at which electron emission from cathode 21 occurs is controlled by a grid controlled valve 30. The plate 30a of valve 30 is connected to cathode 21 via the transformer secondary 26b, and the cathode 30b is connected to a condenser 32 that is charged from the secondary 33b of transformer 33 via rectifier 34. The primary winding 33a of transformer 33 is connected to terminals 35 supplied from an alternating current source. The grid 30c of valve 30 is connected through battery 36 to rotatable winding 37 of a phase shifting device 38 that is powered from 3-phase mains 39 suitably related in phase to the phase of the alternating current supplied at terminals 17. Thus, for example, terminals 17 could be supplied by one phase of the 3-phase mains 39.

The charge on condenser 32 is discharged at the proper instant in each cycle of the alternating current which supplies the electromagnetic field for accelerating the electrons by swinging the potential on the grid 30c of valve 30 with the aid of the phase shifter 38 to render valve 30 conductive. As valve 30 becomes unblocked, the voltage on charged condenser 32 is applied to the cathode 21 and results in emission of a stream of electrons into the tube 18 which are then accelerated in a counter-clockwise direction along orbit k . By adjusting the position of the rotatable winding 37, the instant at which electron injection into tube 18 from cathode 21 takes place as related to the phase of the electromagnetic accelerating field may be varied as desired. Thus, and now referring to Fig. 6, the timing of the switching of the charge potential on condenser 32 to cathode 21 through the valve 30 may be such that the condenser potential is

applied at the start T_1 of a half cycle of the time varied magnetic field B , or if desired, electron injection may be delayed until time T_2 by changing the position of the winding 37 on phase shifter 38. A load resistor 41 for the condenser discharge is connected to the anode of tube 30.

The intensity of the electron stream emitted from cathode 21 can be varied as desired by variation in the resistance 27 which varies the cathode heating effect.

In the interest of simplifying the drawings, the complete circuit by which the electron stream from cathode 20 is independently controlled has not been shown. However, it is operated independently of the above-described circuit and identical with the latter in construction.

If desired, according to a modified form of construction, the current impulse reaching cathode 21 may be switched in by a relay instead of directly through the grid controlled valve 30, in which event the relay would be located in the anode circuit of a valve similar to valve 30.

A modified form of double and independently controlled cathode arrangement for a magnetic induction device is shown in Fig. 3. Here the two cathodes 42, 43 are alike in construction and are controlled, in part, by grids 44, 45 which are placed, respectively, in front of the cathodes. The electron stream injected into the tube 18' from cathode 42 can be adjusted as desired by placing a potential on grid 44 from battery 46 having suitable potential taps for this purpose. In a similar manner, the electron stream injected into the tube from cathode 43 may be adjusted by means of the battery 47 that is connected in circuit with grid 45.

In the Fig. 3 arrangement, initial control over the direction of the electron streams emitted from the cathodes 42 and 43 is provided by right angled plate electrodes 48, 49 which are placed back-to-back to partially enclose and shield the cathodes from each other and a flat plate electrode 50, which may be closest to the orbital path of the electrons, arranged parallel with one side of each of electrodes 48, 49. Electrode 50 is grounded and electrodes 48, 49 are charged negatively or eventually also positively with respect to plate 50 by means of a battery 51 which is provided with a plurality of potential taps by which the potential of electrodes 48 and 49 with respect to electrode 50 may be adjusted independently of each other, the battery being earthed at a point intermediate its electrodes.

With like potentials on electrodes 48 and 50, the direction of the electron stream emitted from cathode 42 is substantially tangent to the outer wall of the annular tube 18'. However by adjusting the taps shown at the left side of battery 51, the potential on electrode 48 may be made negative with respect to electrode 50 and the resulting change in the electrostatic field between these electrodes will then cause the electron stream from cathode 42 to be deflected away from the tangential path, the magnitude of the deflection being dependent upon the extent of the difference in potential between electrodes 48 and 50.

The initial direction of the electron stream emitted from the other cathode 43 at substantially a half cycle later in the induction flux cycle may be changed in a similar manner by altering the position of the voltage tap at the right side of battery 51.

The respective initial directions of the emitted electron streams as selected by the separate ad-

justment of the electrostatic fields between the two sets of electrodes are determinative of the length of time that the electron streams remain in the tube 18', so that in this way, their final velocity can be adjusted separately to the desired extent.

Still another modification of the invention is shown in Fig. 4 in which the injection of the two electron streams is controlled by application of a current impulse to two grids controlling the emission of dual electron streams from a single cathode rather than by application of the control directly to the cathode itself. In this view, the electron tube is designated by 18'', and the single cathode 52 is heated indirectly by means of a filament 52a supplied by transformer 53. Juxtaposed electrode plates 61 which may be charged to like or different potential in the manner shown in Fig. 3, function to control the initial path of the two electron streams emitted alternately and in opposite directions from cathode 52. An initial potential on control grid 54 for cathode 52 that controls acceleration of an electron stream emitted from cathode 52 in a counter-clockwise direction around the tube 18'' is obtained through an adjustable voltage battery 55. The remainder of the circuit for the control of grid 54 is comprised of a relay 56 through which the potential of a condenser 57 is applied to the grid 54, a grid controlled valve 58 for controlling energization of relay 56, a phase shifter 59 powered from 3-phase mains 69 and having a rotatable winding 62 by which the potential on grid 58a of valve 58 is swung periodically to render valve 58 conductive, and a rectifier 63 fed from transformer 64 for charging condenser 57. A load resistor 65 is provided in the connections to grid 54 for the discharge from condenser 57.

The Fig. 4 arrangement operates much in the same manner as that shown in Fig. 2. Briefly, each time that the voltage in winding 62 of the phase shifter 59 reaches its maximum value, the corresponding peak potential on grid 58a renders the valve 58 conductive and a pulse of current flows through the energizing winding of relay 56 which is connected in the cathode-anode circuit of valve 58. The source of anode current for valve 58 is the battery 66. As the relay contacts 56a close, a current impulse from charged condenser 57 is switched in to the grid 54 thus effecting the discharge of an electron stream into tube 18'' for acceleration in a counter-clockwise direction by the time varying magnetic field. The magnitudes of the electron streams leaving cathode 52 can be adjusted by varying the characteristics of the control elements in the circuit. For example, by increasing the voltage at the secondary winding 64b of variable voltage transformer 64, the voltage at condenser 57 and thereby the electron stream produced by cathode grid 54 become larger.

The corresponding circuit for controlling cathode grid 66 by which electron streams are periodically injected into tube 18'' from cathode 52 for acceleration in a clockwise direction around the tube under the influence of the other half cycle of the magnetic induction field is identical with, and independent of, the circuit associated with cathode grid 54. In the interest of simplifying the drawings, this other circuit has been shown only in part with corresponding circuit components indicated by like primed reference numerals.

As explained in an earlier part of this de-

scription, the electron stream in a magnetic induction accelerator is diverted from the equilibrium circle after it has reached the desired velocity maximum and caused to impinge upon a target anode to produce X-ray radiations. According to the present invention, wherein the electron accelerating device operates on both halves of the cycle of the time varied magnetic induction flux and uses alternately discharged and oppositely rotating electron streams, means are provided for independent control over the instants at which these two streams are pulled away from the equilibrium circle as related to the instant magnitude of the induction flux. Referring now to Fig. 5 which illustrates a preferred arrangement for controlling the electron streams independently, the circuit there shown is seen to be comprised of a pair of phase shifters 67, 68 powdered from 3-phase mains 69, a pair of grid control valves 70, 71 which may be thyratrons, and a condenser 72 charged from a transformer 73 through rectifier 74. The rotatable winding 75 of phase shifter 67 is connected in the cathode-grid circuit of valve 70 through battery 76 and resistor 77; the rotatable winding 78 of phase shifter 68 is similarly connected through battery 79 and resistor 80 into the cathode-grid circuit of valve 71.

In the illustrated embodiments of the invention, as typified by the construction shown in Figs. 1 and 5 respectively, the anode 23 impinged upon from opposite directions by the electron streams injected alternately from cathodes 20, 21 is located radially inward from the equilibrium circle k and hence the electron streams must be pulled radially inward from this circle. This of course requires that the magnetic control field acting through the control poles 13-13' be strengthened at the proper instant to thereby increase the centripetal forces acting upon the electron stream so that the latter is driven radially inward. In the present constructional example, strengthening of the control field as shown in Fig. 5 is obtained by means of an auxiliary winding 82 consisting of the two halves 83 and 84 which is placed in the magnetic structure 10 so that when energized periodically by the discharge from condenser 72, the magnetic field set up in winding 82 will increase the total control magnetic field. If the target anode 23 were to be located radially outward from the equilibrium circle k , it would of course be necessary to drive the electron streams radially outward, in which case the auxiliary magnetic field furnished by the additional winding in the magnetic structure 10 would be arranged so as to weaken the centripetal effect of the control field component of the magnetic induction flux.

The components in the Fig. 5 circuit are arranged so that condenser 72 is discharged alternately through the one of the halves of the auxiliary winding 82 once in each half cycle of the alternating current applied to the main induction windings 16-16'. Thus when the induction flux approaches its maximum value in one direction, the electron stream that had been introduced from one of the cathodes such as cathode 20 at substantially the zero point on one half of the induction flux cycle is driven radially inwardly from the equilibrium circle k to impinge upon the target anode 23. As the induction flux reverses and approaches its maximum value in the opposite direction, the condenser 72 is again discharged through the other half of the auxiliary winding 82 and causes the other electron stream that had been introduced by cathode 21 to be

driven radially inward from its accelerating orbit and impinge upon target anode 23 from the opposite direction.

The exact time in the induction flux cycle at which the two electron streams are diverted respectively from the equilibrium circle may be controlled independently of each other by means of the phase shifters 67 and 68. Thus for example, the instant T_3 (see Fig. 6) at which the grid 70a of control valve 70 renders the valve 70 conductive and which thereby permits the condenser 72 to discharge through the auxiliary winding 83 and drive the then accelerating electron stream injected for example at time T_1 radially inward against the target anode 23 may be varied by adjusting the position of winding 75 on phase shifter 67. A change in the time of electron release to the target anode 23 thus changes their maximum speed as may be required to suit a particular condition. The time of release of the other electron stream which follows at substantially a half cycle later in the induction flux cycle may be similarly controlled by varying the position of the winding 78 on phase shifter 68. If desired, electron ejection from the equilibrium circle k may be delayed until time T_4 which coincides with the maximum of the induction flux, in which case the electron streams would both be at maximum velocity.

I claim:

1. A magnetic induction accelerator comprising, a chamber within which charged particles such as electrons may follow a closed orbital path, means adjacent said chamber for producing a cyclically varying magnetic field of alternating polarity, said field having such spacial distribution as to normally confine the electrons to said orbital path while continuously accelerating them along said path, means including electron emission cathode means operated in timed relation with the variation in said magnetic field for periodically injecting electron streams into said chamber for acceleration respectively in opposite directions along said path, the direction of the acceleration of a particular stream being dependent upon the polarity of said magnetic field, means operated in timed relation with the variation in said magnetic field for ejecting the accelerated electron stream of each direction, and independently operated control means individual to the electron streams accelerated in opposite directions respectively for effecting independent changes in a characteristic of the electron streams of each direction.

2. A magnetic induction device as defined in claim 1 wherein the means for controlling electron streams of opposite direction includes means for independent adjustment of the intensity of each stream.

3. A magnetic induction device as defined in claim 1 wherein the means controlling electron streams of opposite direction includes means for independent adjustment of the maximum velocity of each stream.

4. A magnetic induction device as defined in claim 1 wherein the means for controlling electron streams of opposite direction includes means for independent adjustment of the respective periods during which said streams are accelerated.

5. A magnetic induction device as defined in claim 1 wherein the means for controlling electron streams of opposite direction includes means by which the entering angle of said streams may be independently adjusted.

6. A magnetic induction device as defined in

claim 1 wherein consecutive electron streams are discharged into said chamber in response to consecutive current impulses, and the means for controlling the electron streams includes means for adjusting the respective magnitudes of consecutive current impulses independently of one another.

7. A magnetic induction accelerator comprising, a chamber within which charged particles such as electrons may follow a closed orbital path, means adjacent said chamber for producing a cyclically varying magnetic field of alternating polarity, said field having such spacial distribution as to normally confine the electrons to said orbital path while continuously accelerating them along said path, a pair of cathodes, means operated in alternation and in timed relation with the variation in said magnetic field for discharging streams of electrons from one cathode in alternation with electron streams discharged from the other cathode for acceleration respectively in opposite directions along said path, the direction of acceleration of a particular stream being dependent upon the polarity of said magnetic field, means operated in alternation and in timed relation with the variation in said magnetic field for ejecting the accelerated electron streams of each direction, and independently operated control means individual to each said cathode for adjusting the electron emission from one cathode independently of the electron emission from the other cathode.

8. A magnetic induction device as defined in claim 7 wherein said cathodes are heated and said adjusting means includes means for independent adjustment of the heating of each cathode.

9. A magnetic induction device as defined in claim 7 wherein a control potential is applied to each of said cathodes and said adjusting means includes means for adjusting the potential applied to one cathode independently of the potential applied to the other cathode.

10. A magnetic induction device as defined in claim 7 wherein said adjusting means includes means for independent adjustment of the respective intensities of the two electron streams.

11. A magnetic induction accelerator comprising, a chamber within which charged particles such as electrons may follow a closed orbital path, a winding adjacent said chamber and energized from a source of alternating current for producing a cyclically varying magnetic field of alternating polarity, said field having such spacial distribution as to normally confine the electrons to said orbital path while continuously accelerating them along said path, means operated periodically in timed relation with the variation in said magnetic field for periodically injecting electron streams into said chamber for acceleration respectively in opposite directions along said path, the direction of the acceleration of a particular stream being dependent upon the polarity of said magnetic field, auxiliary winding means disposed adjacent said chamber and which when energized produces a magnetic field effective to cause ejection of said electron streams from said path, and independently controlled circuit means for effecting periodic energization of said auxiliary winding means in opposite directions, respectively, in timed relation with the variation in said magnetic field, each said circuit means including a grid controlled valve, an adjustable phase shifter connected to said source of alternat-

ing current and connections between the valve grid and said phase shifter.

12. A magnetic induction accelerator comprising, a chamber within which charged particles such as electrons may follow a closed orbital path, means including a magnetic structure and energizing winding therefor disposed adjacent said chamber for producing a cyclically varying magnetic field of alternating polarity, said field having such spacial distribution as to normally confine the electrons to said orbital path while continuously accelerating them along the path, means operated in alternation and in timed relation with the variation in said magnetic field for periodically injecting electron streams into said chamber for acceleration of successive injected streams respectively in opposite directions along said orbit, the direction of acceleration of a particular stream being dependent upon the polarity of said magnetic field, anode means, means operated in alternation and in timed relation with the variation in said magnetic field ejecting the accelerated electron streams of each direc-

tion from said path and effecting impingement of said streams against said anode means, and independently operated control means individual to the electron streams accelerated in opposite directions respectively for effecting independent changes in a characteristic of the electron streams of each direction.
